UNITED STATES PATENT OFFICE.

GEORGE WILSON, OF TOLEDO, OHIO, ASSIGNOR TO GEORGE WILSON & SONS,
OF SAME PLACE.

BOX-FASTENER.

SPECIFICATION forming part of Letters Patent No. 319,651, dated June 9, 1885.

Application filed July 5, 1884. (No model.)

To all whom it may concern:

Be it known that I, GEORGE WILSON, a citizen of the United States, residing at Toledo, in the county of Lucas and State of Ohio, have 5 invented a new and useful Box-Fastening, of which the following is a specification.

This invention relates to that class of box-fastenings which are commonly used on boxes for shipping beer, soda, and other bottles, in 10 which a detachable lid is locked upon the box by means of an internal concealed, and consequently protected, fastening, and which is operated to unlock or release the lid through a hole in one of the sides of the box.

15 The object of my invention is to provide a simple, cheap, and durable fastening, which shall be self-locking by the act of closing the lid upon the body of the box, and which shall be adapted to be sealed, if desired, by the use 20 of an ordinary car-door compression seal. I attain these objects by the mechanism illustrated in the accompanying drawings, in which—

Figure 1 is a vertical end section of a box having attached my improved fastener. Fig. 2 is also a vertical end section having attached 25 my improved fastener and representing a box as it appears when the cover is open. Fig. 3 is a plan of the striking-plate which forms the cover part of my fastener on line A, Fig. 6. Fig. 4 is a sectional view of the striking-plate 30 on line B, Fig. 3. This view also shows the upper extremity of the locking-spring and the perforation therein. Fig. 5 is a portion of the front elevation on line D, Fig. 1. Fig. 6 shows

35 an elevation of the metallic part of my fastener as it appears when wholly detached from the box, and is similar to the metallic part shown in Fig. 1. Fig. 6 is taken on line E, Fig. 4. Figs. 7 and 8 are two views of a spring 40 made of wire instead of steel plate, which latter are most commonly used.

Similar letters refer to similar parts throughout the several views.

In the drawings, F represents a spring, preferably made of flat steel plate, as shown in 45 Figs. 1, 2, 3, 4, and 6; but a very desirable spring is made of wire, as shown in Figs. 7 and 8. This spring F has a suitable hole, O, or perforation in its upper extremity, the office of

which is to receive the lug or stationary bolt 50 N, hereinafter described.

The spring F is attached to the inside of the box by means of a screw, nail, or staple, as shown in Figs. 1, 2, 6, 7, and 8. The nail, screw, or staple at G, Figs. 1, 2, and 6, and 55 the pintle at G, Figs. 7 and 8, are firmly driven home, and rigidly secure the lower extremity of the spring F to the side of the box H. The screw, nail, or staple at I, Figs. 1, 2, 6, 7, and 8, is only partly driven into the wood to the 60 extent of allowing the requisite movement of the spring F, but no more, and is an effectual check against the careless forcing of the spring F beyond its springing capacity, and is a valuable adjunct for this purpose, while it also 65 serves the purpose of keeping the spring F in proper vertical position.

The spring F may be slightly bent, as shown in Figs. 1 and 2, but this bend is not essential.

The striking-plate S (shown in Figs. 3 and 70 4) is also one of the principal features of this invention, being made in nearly a semicircular form, with a central perforation, O, Figs. 4 and 7, through which the upper extremity of the spring F may pass to nearly a level position with the top of the body of the box, while the outside rim of the said plate S has abundant room for securing screws or nails. The plate S is also provided with a catch bolt or lug, N, of a form adapted to automatically 75 pass through the hole or perforation O in the spring F by the act of closing the cover J of the box.

The spring F is operated upon for the purpose of releasing the cover J by passing through 85 the hole K in the body of the box H a pin, L. This pin L has a head on its inner end and a hole through its outer end, the head, by being larger than the hole K, preventing the pin from passing outward and being lost, the 90 hole in the pin admitting of the use of a sealing-wire, as shown in Figs. 1, 5, and 6.

I am aware that prior to my invention box-fasteners having straight flat springs and bent flat springs turned at various angles at their 95 upper extremities and used in combination with flat striking-plates have been known and used; also various devices for concealed fast-

enings, which were operated through holes in the containing-box; also various methods of sealing said devices with paper labels, &c. I therefore do not claim such combinations, 5 broadly; but

What I do claim as my invention, and desire to secure by Letters Patent, is—

1. In combination with the box H and cover J, the catch-spring F, having a perforation, 10 O, in its upper extremity, and the striking-plate S, having a depending and offsetting lug, N, said lug being adapted to enter the perforation O, for the purpose herein shown and described.

2. The combination, with the box H and the 15 catch-spring F, having a perforation, O, in its upper extremity, of the flat striking-plate S, with its central perforation and its offsetting lug or catch-bolt N, the pin L, having a retaining-head on its inner end and a hole near 20 its outer end, substantially as and for the purpose described.

GEORGE WILSON.
